United States Patent Office

Des. 225,159
Patented Nov. 21, 1972

225,159

TRAILER

Stewart E. Gardner and Ronald J. Bibeau, Bristol, and Charles B. Bonisfield, Fort Wayne, Ind., assignors to Gardner, Inc., Bristol, Ind.

Filed May 28, 1971, Ser. No. 148,282

Term of patent 14 years

Int. Cl. D12—10

U.S. Cl. D14—3

FIG. 1 is a perspective view of the new, original and ornamental design of our trailer showing the front and left-hand side thereof;

FIG. 2 is a side elevational view showing the right-hand side thereof, the hitch elements being shown fragmentarily for illustrative purposes only; and

FIG. 3 is a rear elevational view.

We claim:

The ornamental design for a trailer, as shown and described.
